UNITED STATES PATENT OFFICE.

HENRY BURTON HOUSTON, OF SPOKANE, WASHINGTON, ASSIGNOR OF ONE-HALF TO
GEORGE T. HANSEN, OF SALT LAKE CITY, UTAH.

SHAMPOO SHIELD.

Application filed February 12, 1923. Serial No. 618,748.

To all whom it may concern:

Be it known that I, HENRY BURTON HOUSTON, a citizen of the United States, residing at Spokane, in the county of Spokane and State of Washington, have invented a certain new and useful Improvement in Shampoo Shields, of which the following is a full, clear, concise, and exact description, reference being had to the accompanying drawings, forming a part of this specification.

My invention relates to shields for protecting the face and eyes when washing, rinsing, or otherwise treating the head, scalp or hair.

I am aware that protection of this sort without which the water, suds or other fluid will run down over the face and into the eyes, has been proposed heretofore. Such shields with which I am familiar are however stretched down over the top of the head. In a barber shop the person usually remains in the chair while the head is soaped. A shield is not necessary at that time and would in fact interfere with the proper soaping of the head. After proper soaping or other treatment, the person is directed to a bowl or basin, and upon bending his head forwardly over the same the shampoo is completed and water is applied to rinse out the soap, and it is at that time that a shield is desirable. If a shield were stretched over the top of the head after soaping, some of the suds at least, would be forced down onto the face below the shield and into the eyes. Furthermore, such shields are irritating when in place and to secure attachment to the head, and a drain, expensive, complicated and cumbersome constructions have resulted.

According to my invention, the shield is formed to admit the face and is provided with a marginal edge formed to conform to the face about the lower edge of the hair. This permits soaping the head first, and then applying the shield to the face or the face to the shield as distinguished from stretching a shield down over the top of the head, and avoids forcing the suds down onto the face and into the eyes as well as the irritation caused by and difficulty of attachment of a shield to the head. The edge of the shield is simply properly engaged with the face about the lower edge of the hair,

said edge being preferably sufficiently yieldable or flexible to conform snugly or closely to the various face contours presented thereto.

I contemplate the provision of sanitary covers for application to and removal from the edge of the shield presented to the face, as well as a drain for draining off the suds, water or other fluid, so that it cannot possibly reach the face or eyes. I further provide for supporting the shield either manually or for fixedly or removably attaching the same to a stand or to the bowl or basin. A more specific feature is the provision of a frame which, in addition to serving as a frame, functions as a combined support and drain for the device.

In addition to the provisions and advantages above set forth, it is an aim of my invention to provide a simple and inexpensive device, the use of which will be simple and with no more effort than now required in shampooing without a shield.

In order to apprise those skilled in the art with the manner of constructing and utilizing my invention, I shall now describe a specific embodiment of the invention in connection with the accompanying drawings which form a part of this specification.

In the drawings:

Figure 1 is a side elevational view of a shield embodying my invention, showing the same applied to the face;

Fig. 2 is a top plan view of the shield;

Fig. 3 is a detail cross-section taken on line 3—3 of Fig. 2;

Fig. 4 is a detail cross-section taken on line 4—4 of Fig. 1 showing a sanitary cover for the upper edge of the shield;

Fig. 5 is a fragmentary perspective view of the sanitary cover shown in Fig. 4 and in dotted lines in Fig. 1;

Fig. 6 is a fragmentary perspective view showing a shield embodying my invention detachably and adjustably secured to a basin or stand;

Fig. 7 is a top plan view of a modification; and

Fig. 8 is a top plan view of another modification formed integral or as a part of a stand or basin.

The shield shown in Figs. 1, 2 and 3 comprises a frame 5 of substantially horseshoe or U-shaped formation, shaped generally to

the contour of the face around the edge of the hair. The frame 5 may be of sheet metal or any other suitable material and is preferably channel-shaped in cross-section, as shown in Fig. 3, for a purpose which will hereinafter appear. A flat band, sheet or strips 6, preferably of rubber, although paper and other flexible materials are contemplated within the scope of my invention, is secured along its lower edge as by riveting, cementing or otherwise, to the inner flange 8 of the channel frame 5. The frame 5 shapes the band 6 generally to the contour of the face, the upper edge of band 6 defining an opening for the reception of the face, as shown at 10 (Fig. 1), upon presenting the face to the band or the upper edge of the band to the face about the edge of the hair.

Adjacent the opposite end of band 6 the ends of channel frame 5 are pressed together, as shown at 11, to close the channel beyond the ends of the band, the ends of the channel frame projecting as shown to provide handles 12 which may be grasped in the hands to hold the shield manually in place, or secured in a stand for supporting the shield. The frame is preferably sufficiently springy or yieldable, so that when the face is presented to the upper edge of band 6 it will spread, if necessary to permit the band to conform closely to the face. The yieldable upper edge of the band will give sufficiently to conform closely or snugly to the different face contours presented, and in fact the yieldability of the band itself will, in some instances, be sufficient without any yieldability of the frame 5.

In use, the upper edge of band 6 is applied to the face about the edge of the hair. This may be done simply by bending over the bowl or basin and supporting the shield manually or otherwise in position to receive the face or by presenting the shield to the face and then bending over. With the upper edge of the shield in snug engagement with the face, the water or fluid applied is directed down along the outside of band 6 away from the face and eyes and into the drain gutter formed along the lower edge of band 6 by frame 5. In rinsing, the head is usually inclined forwardly about as shown in Fig. 1, and the outer flange of channel frame 5 is therefore cut away at the front, as shown at 15, to permit the suds or other fluid to flow out of the front of the gutter and away from the face. Possible dripping from the edge of band 6 onto the face and into the eyes is thereby prevented. If the shield is inclined rearwardly when in use, the outlet opening may be at the rear or at any other suitable or desired point.

It will now be apparent that the shield is of simple and inexpensive construction and that it may be applied after the head is

soaped, without forcing the suds down onto the face and into the eyes. Furthermore, its use is simple and with no more effort than now required without a shield.

To the end of sanitation, I provide sanitary covers 16, preferably of paper or any other suitable material, one of which is slipped over the upper edge of band or strip 6 before each use. After use, the cover is removed and thrown away, a quantity being kept in stock so that a fresh one may be slipped on and a clean surface thereby presented to each face. These covers may be of channel formation, as shown, to straddle the upper edge of band 6 and made up in strips of the proper length.

In Fig. 6 I have shown a shield embodying my invention detachably and adjustably secured to the bowl or basin 20 over which the head is washed or rinsed. The shield 85 comprises a frame 21 shown of channel formation with an outlet 23 at the front, as before, and a flexible band or strip 22 secured along its lower edge to frame 21, and projecting upwardly therefrom to admit the 90 face into engagement with its upper edge. The projecting ends 24 of frame 21 are bent downwardly and telescope upon the upper ends of posts 25, the lower ends of which are hooked, as shown at 26, to engage the down-turned flange 28 of bowl or basin 20. The hooked ends 26 of posts 25 are preferably provided with rubber tubes 30 or other suitable coverings so as not to mar the bowl which is usually enameled and highly finished.

Posts 25 are offset at 32 and a strip 34 connecting these offset portions 32 carries a headed clamping screw 35. Clamping screw 35 threads through strip 34 and is provided with a rubber or other yieldable head 36 for clamping engagement with the surface 38 of bowl 20. Screw 35 clamps rods 25 and shield carried thereby securely in place, and its range of thread or adjustment allows proper accommodation to bowl rims of different dimensions. Sleeved ends 24 of frame 21 are secured in place on posts 25 by screws 40, which screws permit adjustment of the shield vertically and provide for securely clamping the same in adjusted position. The shield may of course be clamped into any other suitable stand instead of the bowl or basin over which the head is rinsed.

In the modification shown in Fig. 7, the channel frame 42 is of substantially oval formation closed at its opposite ends, as shown at 43. As before, the flexible band or strip 44 is suitably secured to the frame, so as to conform thereto and projects upwardly therefrom to receive the face. A handle 45 which may of course be formed integrally with frame 42 instead of independently thereof, as shown, is provided for holding the shield manually or

the shield may be supported in a stand through said handle. The handle 45 is riveted or otherwise suitably attached to frame 42, and at the same time serves to secure the adjacent ends of frame 42 and band or strip 44 together. A drain opening 46 is provided at the forward portion of channel frame 42.

In the embodiment shown in Fig. 8 the shield is formed as an integral part of the bowl or basin 50 over which the head is washed or rinsed, the frame 52 which supports the yieldable shield 53 being connected through arms 55 with bowl or basin 50. The bowl or basin 50 need not be large, and is provided in this case simply for use in shampooing or other treatment of the hair. As in the embodiment shown in Fig. 7, the shield is of closed oval formation, and projects upwardly from the frame to receive the face and conform to the face about the edge of the hair, yieldability of the upper edge of the shield permitting a close or snug fit against the face.

25 A tube may be led from the discharge openings of the gutters of any of the devices to drain the fluid to any desired point. The sanitary covering may comprise simply sheets or strips of tissue paper folded over the upper edge of the shield.

The provision of a shield formed to admit the face and to conform thereto about the edge of the hair, as distinguished from shields stretched over the head as well as 35 the gutter, supporting and frame arrangement, and provision for mounting the device adjustably and detachably, as well as the provision for forming the device as a part of the bowl or basin and the sanitary 40 cover are highly important aspects of my invention.

I do not intend to be limited to the details shown or described.

I claim:

45 1. In a shield for use in the treatment of the hair, a flat shield member formed to admit the face and having sides for directing the substance applied to the hair away from the face and eyes.

50 2. In a shield for use in the treatment of the hair, a flat, pliable band formed to admit the face and having an edge conforming to the face about the lower edge of the hair and sides for directing the substance applied to the hair away from the face and eyes.

55 3. In a shield for use in the treatment of the hair, a band formed to admit the face and having an upper edge conforming to 60 the face about the lower edge of the hair and sides for directing the substance applied to the hair away from the face and eyes, and a gutter about the opposite edge of said band.

65 4. In a shampoo shield, the combination

of a frame formed generally to the contour of the face and a flexible band defining an opening for the reception of the face, said band having its lower edge attached to the frame and its upper edge conforming to the 70 face about the lower edge of the hair.

5. In a shampoo shield, the combination of a flat, yieldable band defining an opening for the reception of the face, said band having its upper edge conforming to the face 75 about the lower edge of the hair, and a drain gutter about the lower edge of said band.

6. In a shampoo shield, the combination of a band defining an opening for the reception of the face, said band having its upper edge conforming to the face about the lower edge of the hair, and a frame about the lower edge of said band, said frame constituting a drain for the shields.

7. In a shield for use in the treatment of the hair, a flat, yieldable shield member formed to admit the face and having sides for directing the substance applied to the hair downwardly and forwardly away from 90 the face and eyes.

8. A shampoo shield comprising a band disposed vertically on edge formed to admit and fit the forehead and sides of the 95 face and a drain gutter about the lower edge of said band.

9. In a shield of the class described, the combination of a band adapted for application to the head, a V-shaped frame for said band having leg extensions beyond the 100 band, said frame constituting a drain for the shield.

10. In a shield of the class described, the combination of a flexible band disposed vertically on edge and formed to admit the 105 face, and means for supporting said band, said supporting means constituting a drain for the device.

11. In a shield of the class described, the combination of a thin, flat, pliable band disposed vertically on edge to admit and fit the forehead and sides of the face, said band having a marginal edge for presentation to the face, and a removable sanitary cover for said marginal edge.

12. In combination, a stand, a frame attached to said stand and formed generally to the contour of the face, and a flexible band carried by said frame and formed to admit the face, said frame forming a drain at the bottom edge of the band.

13. In combination, a stand, a shield comprising a frame formed generally to the contour of the face, and a flexible band carried by said frame, and means for detachably securing the shield to said stand, said frame forming a drain at the bottom edge of the band and having an outlet at the front.

14. In combination, a stand, a shield

130

comprising a channel frame formed generally to the contour of the face, a flexible band carried by said frame and adapted to fit the face from forehead to chin, and 5 means for attaching the shield to said stand, said means being adjustable to permit adjustment of the position of the shield.

15. In combination, a stand, a frame carried thereby, a flexible band attached along 10 its lower edge to the frame and having its upper edge formed to admit the face.

16. In a shield of the class described, the combination of a U-shaped band of thin, pliable material disposed on edge and 15 adapted to fit the contour of the face at the forehead and sides, of a U-shaped frame for said band and forming a drain below its top edge, the sides of the frame extending beyond the sides of the band and the 20 frame constituting a drain for the shield.

17. A shampoo shield comprising a flexible strip of material formed to fit the con-

tour of the face beneath the lower edge of the hair when bending over so as to drain suds and fluid matter away from the face 25 and prevent access thereof to the eyes, nose and mouth, and a drain channel at the bottom edge of the strip at the outside only and projecting outwardly therefrom.

18. A shampoo shield including a band 30 formed to admit and conform to the face from underneath when bending over and having its upper edge conforming to the forehead and sides of the face with the face projecting into the band whereby the hair 35 and top of the head is exposed, said band adapted to direct substance applied to the hair away from the face and eyes, and a gutter at the bottom edge of the band at the 40 outside.

In witness whereof, I, hereunto subscribe my name this eighth day of February, 1923.

HENRY BURTON HOUSTON.

Certificate of Correction.

It is hereby certified that in Letters Patent No. 1,524,863, granted February 3, 1925, upon the application of Henry Burton Houston, of Spokane, Washington, for an improvement in "Shampoo Shields," an error appears in the printed specification requiring correction as follows: Page 3, line 99, claim 9, for "V-shaped" read *U-shaped*; and that the said Letters Patent should be read with this correction therein that the same may conform to the record of the case in the Patent Office.

Signed and sealed this 24th day of March, A. D. 1925.

[**SEAL.**]

KARL FENNING,
Acting Commissioner of Patents.
